UNITED STATES PATENT OFFICE.

PATRICK H. CUMMINS, OF AMSTERDAM, NEW YORK.

WHEEL.

SPECIFICATION forming part of Letters Patent No. 393,218, dated November 20, 1888.

Application filed March 24, 1888. Serial No. 208,374. (No model.)

To all whom it may concern:

Be it known that I, PATRICK H. CUMMINS, of Amsterdam, in the county of Montgomery and State of New York, have invented certain 5 new and useful Improvements in Wheels; and I do hereby declare that the following is a full, clear, and exact description thereof, reference being had to the accompanying drawings, and to the letters of reference marked thereon, 10 which form part of this specification, in which—

Figure 1 is a side view of my improved wheel, the felly being partly in section to show the attachment of the spokes thereto. Fig. 2 is a detail side view of the same, partly in 15 section, the felly and spokes being broken away. Fig. 3 is a detail side view of a modified construction of the hub. Figs. 4 and 5 are detail views of a modification. Figs. 6, 7, and 8 are detail views of the spoke-fastenings.

20 This invention relates to improvements in wheels; and its objects are to provide a knock-down-wheel that can be readily and quickly put together or taken apart, to provide an adjustable sectional compensating hub that will 25 automatically adjust itself to compensate for strain on the spokes and fellies, and to improve the fastening of the spokes to the fellies or rim and to the hub-sections.

The invention consists in the novel construction and arrangement of parts for effecting the above objects, as will be fully understood from the following description, taken in connection with the accompanying drawings, and concisely stated in the annexed 35 claims.

Referring to the drawings by letter, A designates a sleeve or shaft, and B are similar oppositely-facing disks or hub-sections thereon, which disks have the central ring portions, 40 b, by which they are supported on the sleeve. The portions b may be provided with lugs on their inner faces engaging in grooves in the sleeve or shaft or secured thereon in other proper manner, so that the sections B will turn 45 with the sleeve or shaft, but have free lateral play thereon.

On the flaring portions of disks B are formed the radial series of outstanding curved flanges C, the apex of said flanges being toward the 50 axis of the hub, as shown.

c c designate lips projecting inwardly from

the upper edges of the apexes of flanges C, as shown, and I preferably leave openings in the flaring portions of the disk below lips c, so that the said disk can be cast without the employment of cores. 55

D D are coiled springs placed on sleeve A between the disks B, and separated by a central collar, a, on said sleeve or axle, so that each spring will act against the adjoining disk 60 independently of the other. If desired, a single coiled spring might be employed, the collar a dispensed with, and the spring secured centrally to the axle or sleeve, its opposite portions then having precisely the same functions as the independent spring D, described. The object of this arrangement of springs is hereinafter explained. 65

E designates the spokes, which are in pairs, made of rods or wires bent like the letter V. The 70 ends of the spokes are headed, as shown, to pass through openings f in the felly of the wheel.

The felly F is provided with a series of equidistant openings, f, corresponding in number 75 to the spokes of the wheel, and adjoining each opening f is a similar opening, G, communicating with the former opening by a slot, g, which corresponds in diameter to the thickness of the spokes. The headed ends of the spokes 80 are passed through openings f. Then the spokes are slipped laterally through slots g into openings G, which, being smaller in diameter than the headed ends of the spokes, will effectually prevent the retraction of the latter there- 85 through and likewise prevent the lateral escape of the spokes through slots g. Openings G are countersunk to receive the heads of the spokes. I preferably enlarge the diameter of the spokes 90 adjoining their heads, as shown, and then increase the diameter of opening G to correspond with the enlargement, thereby more effectually preventing the lateral escape of the spokes through slots g; or, instead of enlarging the headed ends of the spokes, I head them as before, pass them through the opening f and the slot g into openings G, and before seating the headed ends in openings G slip on the spokes below their heads conical bushings or arbors H, which may be made in sections or made of 95 malleable metal, split, and then clamped around the end of the spokes after the latter have been

100

passed through the openings *f*. The bushing *H* will enter openings *G*, in which they fit snugly, and effectually secure the spokes therein. In some instances I prefer to use only the 5 openings *f*, these openings permitting the passage of the headed ends of the spokes on which the bushings are then placed, and the latter seat themselves in the openings and prevent the withdrawal of the spokes, as shown.

10 In setting up a wheel the springs are first placed on the sleeve or shaft *A*. Then the disks *B B* are placed on the sleeve. The proper number of twin spoke-rods are then secured in the openings of the felly, as described, with their 15 bent ends inward. The disks *B B* are then forced toward each other by suitable clamps compressing the springs, and the bent portion of the twin spokes slipped over the adjoining flanges *C* of the disks and under the lips *c c* of 20 said flanges. The disks are then released, and springs *D D*, acting against them, force them apart on shaft *A*, causing them to tighten the spokes *E* instantaneously and hold them taut, as will be evident from the drawings. The collar 25 on the shaft *A*, or the point of attachment of the springs thereto, is in the plane of the felly, and will keep the latter true with the hub, preventing dishing of the wheel, and as either hub-section is partially independent of 30 the other any lateral strain on the wheel and consequent flexing of the spokes of a disk will be immediately taken up by the action of the spring against such disk. The spokes radiating from each disk are secured to the felly alternately with the spokes of the opposite disk. 35

It will be observed that by simply compressing springs *D* and forcing disks *B B* toward each other I can flex the spokes so that they can be readily unhooked from the flanges *C*, 40 thus enabling the wheel to be quickly taken apart for transportation, storage, or for repairs. It will further be observed that I can secure the spokes to the felly previous to attaching them to the disk, or disengage them 45 from the latter without disturbing their attachment to the felly, or vice versa.

In Figs. 4 and 5 I cut away or form the flaring portions of the disks so as to leave merely a narrow outer ring, and connect this ring 50 with the portions by means of the radial bent arms *C'*, which answer the same purpose as flanges *C* and lips *c*, already described, but do not permit the engaging or disengaging of the spokes therefrom unless the latter are disengaged from the felly. In either case, however, 55 by compressing the springs and drawing the disks toward each other I can readily disen-

gage the spokes from the fellies and disks, and in the first instance the spokes can be attached to the disks or to the felly, and in the latter 60 case to the disk for transportation, and when ready to be set up can be quickly secured to the disk or to the felly by the means described. It will be seen that I use no screw-threads, require no riveting in setting up the wheel, and 65 that the independently-movable disks will automatically compensate flexing of the spokes and "true" the wheel.

When the wheels are to be used on stationary shafts, the keys and sleeves can be dispensed with and the disks turn freely on the shaft or axle. In such instances the springs may be arranged loosely on the shaft between the disks and turn with the latter, so that they still hold the disks apart. 70

Having described my invention, I claim—

1. The combination of the collared shaft or sleeve and the laterally-movable disks thereon at opposite sides of the collar, with the springs interposed between said disks and the collar 80 on the shaft, and the felly and spokes, substantially as described.

2. In a wheel, the combination of the fellies and spokes with a shaft or sleeve, two opposite hub-sections or disks mounted thereon and turning therewith, but each being independently and laterally movable thereon, and springs on said shaft between and controlling said disks, all substantially as and for the purpose specified. 85

3. The combination of the shaft or sleeve with the laterally-movable disks *B B*, mounted thereon, having flanges *C*, lips *c*, the interposed springs between said disks, and the felly and spokes, substantially as and for the purpose 95 described.

4. The combination of the independently-movable disks *B*, constructed substantially as described, and the interposed springs *D D*, controlling the disks, with the felly having a 100 series of openings, the pairs of spokes *E*, engaging with disks *B*, and having headed ends passed through openings in the felly, and the bushing *H*, placed on the ends of the spokes to secure them to the felly, all constructed and 105 arranged substantially as and for the purpose described.

In testimony that I claim the foregoing as my own I affix my signature in presence of two witnesses.

P. H. CUMMINS.
